CLAIM

The ornamental design for a motorized scooter, as shown and described.

DESCRIPTION

FIG. 1 is a front perspective view of a motorized scooter in accordance with our new design;

FIG. 2 is a rear perspective view thereof;

FIG. 3 is a first side view thereof;

FIG. 4 is a second side view thereof;

FIG. 5 is a front view thereof;

FIG. 6 is rear view thereof;

FIG. 7 is a top view thereof; and,

FIG. 8 is a bottom view thereof.

The shade lines shown in the drawing represent the three-dimensional contour of the motorized scooter, and are not intended to indicate surface decoration.

The features shown in broken lines are for the purposes of illustrating portions of the motorized scooter which form no part of the claimed design.
